US0D1080276S

(12) United States Design Patent (10) Patent No.: US D1,080,276 S
(45) Date of Patent: * Jun. 24, 2025

(54) TABLES

(71) Applicant: KIMBALL INTERNATIONAL, INC.,
Jasper, IN (US)

(72) Inventor: John Nelson, Sr., Philadelphia, PA (US)

(73) Assignee: Kimball International, Inc., Jasper, IN (US)

() Term: 15 Years

(21) Appl. No.: 29/837,145

(22) Filed: May 2, 2022

(51) LOC (15) Cl. 06-03

(52) U.S. Cl.

USPC D6/692.3; D6/692.4

(58) Field of Classification Search

USPC D6/329, 334, 349, 355, 360, 685, 690,
D6/692, 692.1, 692.2, 692.3, 692.4,
D6/692.5, 692.6, 708, 708.16, 708.17,
D6/708.2

CPC A47B 7/00; A47B 13/023; A47C 9/00;
A47C 7/002
